UNITED STATES PATENT OFFICE.

VICTOR ANGERER, OF PHILADELPHIA, PENNSYLVANIA, ASSIGNOR TO
WILLIAM WHARTON, JR., AND COMPANY, INCORPORATED, OF SAME
PLACE.

RAIL-JOINT.

SPECIFICATION forming part of Letters Patent No. 431,835, dated July 8, 1890.

Application filed May 5, 1890. Serial No. 350,573. (No model.)

To all whom it may concern:

Be it known that I, VICTOR ANGERER, a citizen of the United States, and a resident of Philadelphia, Pennsylvania, have invented 5 certain improvements in Rail-Joints, of which the following is a specification.

The object of my invention is to construct an improved rail-joint adapted to secure two flat rails together in line with each other.

10 My invention is especially applicable in securing the rail-sections of a portable railway-track and portable cross-overs.

In the accompanying drawings, Figure 1 is a plan view illustrating the improved rail-joint. Fig. 2 is a side view. Fig. 3 is a section on the line 1 2, Fig. 1; and Fig. 4 is a perspective view of a plate detached.

15 A A' are the two rails, which in this instance are shown as grooved rails; but it will be understood that other forms of rails may 20 be used without departing from my invention.

B is a plate of the peculiar form shown in Fig. 4, having an upwardly-bent lip b at one side at right angles to the base of the plate, 25 while at the opposite side of the plate is an upwardly and inwardly bent lip d, inclined longitudinally in respect to the lip b. The plate B is secured to the rail A by rivets or bolts a a, and the end of the rail A' is adapted 30 to the projecting portion of the plate and abuts against the rail A. Pins c c, secured in the present instance to the lip b of the plate by riveting, are adapted to holes e e in the edge of the rail A', preventing the rail 35 from moving longitudinally. Between the opposite side of the rail A' and the lip d of the plate B is a wedge D, which is prevented from moving longitudinally by a bolt f, which passes through a slot g in the lip d and into 40 the body of the wedge, thus securing the wedge in place after it has been driven up. The rail A' can be readily removed from the rail A by first withdrawing the bolts f, then forcing out the wedge D and moving the rail 45 laterally to free it from the pins c, after which

it can be moved either vertically or longitudinally. The screw-bolt f not only holds the wedge in place after said wedge has been driven, but also confines the wedge to the plate and prevents it from being lost during 50 transportation, as it will be understood that this joint is intended mainly for use in connection with portable cross-overs which are laid upon the surface, the rails not being fastened down.

55

I claim as my invention—

1. The combination of the rails with the tie-plate secured to one of said rails, and having flanges, one of which is tapered, with a wedge adapted to fit between the edge of the 60 rail and the tapered flange, substantially as and for the purpose set forth.

2. The combination of the abutting rails A A', the plate secured to the rails A, and projections or pins connecting the rail A' and 65 the plate, substantially as specified.

3. The combination of the abutting rails A A', the flanged plate secured to the rail A, and projections on the flange adapted to 70 offices in the rail A', substantially as set forth.

4. The combination of the abutting rails, the plate secured to one of said rails, flanges on said plate, with a projection on one of said flanges, and a wedge inserted between the opposite edge of the rail and the opposite 75 flange, said rail having a hole in which the projection rests, substantially as described.

5. The combination of the abutting rails, a plate secured to one of said rails, and having flanges, one of which is tapered and slot- 80 teted, as described, with a wedge and a securing-bolt adapted to said slot in the flange and to the wedge, substantially as set forth.

In testimony whereof I have signed my name to this specification in the presence of 85 two subscribing witnesses.

VICTOR ANGERER.
